CLAIM

The ornamental design for a storage container for magnetic media, as shown and described.

DESCRIPTION

FIG. 1 is a top perspective view of a storage container for magnetic media, showing my new design;

FIG. 2 is a bottom perspective view thereof;

FIG. 3 is an enlarged perspective view thereof, shown open;

FIG. 4 is a rear elevational view of FIG. 1;

FIG. 5 is a reduced top plan view of FIG. 3;

FIG. 6 is a left side elevational view of FIG. 1; and,

FIG. 7 is a bottom plan view of FIG. 1.

FIG. 1

FIG. 2

FIG. 3

FIG. 4

FIG. 5

FIG. 6

FIG. 7
